Primary Examiner—B. J. Bullock**Attorney, Agent, or Firm—Greer, Burns & Crain, Ltd.****[57] CLAIM**

The ornamental design for a vacuum lid attachment for hair clippers, as shown and described.

DESCRIPTION

FIG. 1 is a perspective view of a vacuum lid attachment for hair clippers showing my new design, the broken lines showings of a hair clipper and vacuum being illustrative purposes only and form no part of the claimed design;

FIG. 2 is a right side view thereof;

FIG. 3 is a top view thereof;

FIG. 4 is a left side view thereof;

FIG. 5 is a bottom view thereof;

FIG. 6 is a front view thereof; and,

FIG. 7 is a rear view thereof.

FIG. 1**FIG. 2****FIG. 3**

FIG. 4***FIG. 5******FIG. 6******FIG. 7***
